GRASS CATCHER FOR ROTARY MOWER

Raymond K. Strasel, Winthrop Harbor, Ill., assignor to
Jacobsen Manufacturing Co., Racine, Wis., a corpora-
tion of Wisconsin

Application September 9, 1957, Serial No. 47,669

Term of patent 14 years

(Cl. D40—1)

Fig. 1 is a front perspective view of a grass catcher for rotary mower, showing my new design.

Fig. 2 is a top plan view of the catcher shown in Fig. 1.

Fig. 3 is a left side elevational view of the catcher shown in Fig. 1.

Fig. 4 is a rear elevational view of the catcher shown in Fig. 1.

I claim:

The ornamental design for a grass catcher for rotary mower, substantially as shown.
